UNITED STATES PATENT OFFICE.

BROR MAX SCHAUMAN, OF PHILADELPHIA, PENNSYLVANIA, ASSIGNOR TO HIMSELF, ELLWOOD BEVAN, AND VANCE W. MILLS, OF PHILADELPHIA, PENNSYLVANIA.

STEAM-ENGINE.

SPECIFICATION forming part of Letters Patent No. 770,985, dated September 27, 1904.

Application filed March 10, 1904. Serial No. 197,495. (No model.)

To all whom it may concern:

Be it known that I, BROR MAX SCHAUMAN, a subject of the King of Sweden and Norway, residing at Philadelphia, in the county of Philadelphia and State of Pennsylvania, have invented certain new and useful Improvements in Steam-Engines, of which the following is a specification.

My invention relates to improvements in that class of steam-engines known as "rotary-piston" engines; and my improvements embody a construction by which the wear upon the piston will be materially reduced and the joints between the stationary and movable parts rendered practically tight.

My invention embodies, further, details of construction applicable generally to steam-engines, but capable of being embodied in other like types of motors.

The preferred embodiment of my present invention is illustrated in the accompanying drawings, wherein—

Figure 1 represents a side elevation of my improved steam-engine; Fig. 2, an end elevation looking from the left-hand side of Fig. 1; Fig. 3, a vertical section taken on the line 3 3 of Fig. 2; Fig. 4, a longitudinal section on line 4 4 of Figs. 2 and 3; Fig. 5, a detached perspective view of the plunger; Fig. 6, a perspective view of one of the end packing-rings; Fig. 7, a perspective view of one of the cylinder-heads, and Fig. 8 a perspective view of one end of the rotary piston.

Referring to the reference-letters of the drawings, A represents the cylinder of my engine, in which is arranged a piston B, having a shaft B' supported by the cylinder-heads A' and A'', provided with glands or stuffing-boxes a' and a''. The cylinder A is provided with a receiver or steam-chest A³, provided with a steam-supply pipe a³, leading to a compartment a⁴, which projects downwardly at its two extremities and terminates in ports a⁵ and a⁶, leading into the ends of the cylinder A. The receiver A³ is also provided with a radially-slotted opening a⁷, extending the full width of the receiver, which is adapted to receive a correspondingly former plunger A⁷, whose func-

tion is to divide the cylinder into two parts, and thus separate the pressure side X from the exhaust side X'. The plunger A⁷, which is better illustrated in Fig. 5, is provided at the lower end with a shoe A⁸, fulcrumed to the plunger at a point a⁸, and with arms a⁹ a⁹, fulcrumed to the plunger at one end by a rod a¹⁰ and at the other connected to a shaft a¹¹. The arms a⁹ a⁹ are contained in an exhaust-chamber A⁹, from the upper wall or cover of which projects a discharge-pipe a¹². The plunger is caused to closely engage the end walls of the receiver A³, and thus form a practically steam-tight joint by means of metallic packing-strips a¹³ a¹³, located in recesses a¹⁴ a¹⁴ and normally pressed outward by springs a¹⁵ a¹⁵, surrounding fixed plungers a¹⁶ a¹⁶. The plunger is cut away on one side, forming a groove a¹⁷, the purpose of which is to allow ample space for steam to reach the back of the plunger, so that it will not be retarded in its downward movement, which is further prevented by making the slotted opening a⁷ wider than the greatest width of the plunger, as shown in Fig. 3.

The piston B has a central eccentric portion B² and end disks or heads B³ B³, which are concentric with respect to the shaft B'. The ends of the cylinder A adjacent to the piston-heads B³ B³ are counterbored, leaving ample space for packing-rings C and C', which are in the form of double split rings recessed at the top at c (see Fig. 6) to clear the depending portion of the receiver A³. Between the piston-heads B³ and cylinder-heads A' on either side of the cylinder A is left sufficient space for the passage of steam from the ports a⁵, which passing through said ports and over the packing-rings C C enters this space and from thence enters ports or openings b b in the heads B³ B³. The eccentric portion B² of the piston does not come directly in contact with the inner wall of the cylinder A, but is grooved out at the point of nearest approach and provided with a shoe B⁵, fulcrumed at a point b⁵. This shoe bears against the inner wall of the cylinder and is kept in close contact by the admission of steam di-

rectly below the shoe on one side of its fulcrum - point, which entering the ports b b traverses the groove below the shoe and escapes through the space b^4 between the shoe 5 and piston into the space X. In order to prevent the steam from blowing through from the pressure side X to the exhaust side X' when the shoe B⁵ is adjacent to the chamber A⁹, the cylinder-heads A' and A² are provided 10 with plates D D, resting in grooves D' D', which plates cover the ports b b at this point and cut off the supply of steam until the shoe B⁵ has passed over into the pressure side X. The plates D D are provided with openings 15 to receive plungers d² d², around which are coiled springs S S to retain these plates in position against said plates. The cylinder-heads A' and A² rest against shoulders e and e', formed by an outer counterbore at both ends 20 of the cylinder A, and these heads are firmly held against the shoulders by threaded rings E and E', which are adapted to correspondingly-threaded ends of the cylinder A.

Having described my invention, what I 25 claim, and desire to secure by Letters Patent, is—

1. A steam-engine comprising a cylinder, an eccentric piston, a plunger working in conjunction with the piston to separate the live- 30 steam area from the exhaust area of the cylinder, a receiver provided with ports leading to the ends of the cylinder and concentric heads connected to the piston having ports leading from the outer ends of the cylinder to the periphery of the piston, substantially as specified.

2. A steam-engine comprising a cylinder, a rotary piston mounted therein, having steam-ports, passing from the ends to the periphery 40 thereof, a receiver mounted upon the cylinder having steam-ports leading to the ends of the cylinder, and an exhaust-port leading from the center of the cylinder, a plunger suitably guided in the receiver, and a shoe fulcrumed 45 to the piston and adapted to engage the inner wall of the cylinder, substantially as specified.

3. A steam-engine comprising a cylinder, a rotary piston mounted therein provided with steam-ports, plates mounted at the ends of the 50 cylinder adapted at predetermined intervals to close said ports, a receiver provided with steam inlet and exhaust ports and a plunger guided in the receiver, substantially as specified.

55 4. A steam-engine comprising a cylinder, a rotary piston mounted therein, provided with steam-ports, a shoe fulcrumed to the piston

and having one of its sides arranged above the steam-inlet passage of the piston, a receiver provided with inlet and discharge ports and a plunger guided in said receiver, substantially as described. 60

5. A steam-engine comprising a cylinder, a rotary piston mounted therein and provided with steam-ports, a shoe fulcrumed to the piston in such a manner as to be forced outward against the inner wall of the cylinder by the incoming pressure of steam, a receiver provided with inlet and discharge passages, a plunger guided in the receiver, and a shoe 65 fulcrumed to the end of the plunger and adapted to bear against the piston as it revolves, substantially as specified. 70

6. A steam-engine comprising a cylinder, a rotary piston composed of concentric end disks 75 and an eccentric middle section, the former of which are provided with steam-inlet ports, a receiver provided with inlet and discharge ports and a plunger guided in said receiver, substantially as described. 80

7. A steam-engine comprising a cylinder counterbored at its ends, a receiver provided with inlet-ports and a discharge-port, the former terminating in the counterbored portion 85 of the cylinder, a piston composed of concentric end disks and an eccentric middle portion, the former of which have steam-inlet passages, leading to the middle portion, packing-rings surrounding the end disks and adapted to be held in place by the surrounding steam-pressure and a plunger guided in the receiver, 90 substantially as specified.

8. A steam-engine, comprising a cylinder, a rotary piston mounted therein having steam-inlet ports, a receiver provided with inlet and discharge ports, a plunger guided in said receiver and spring-actuated packing-plates 95 guided in the ends of the plunger, substantially as described.

9. A steam-engine, comprising a cylinder, 100 a rotary piston mounted therein having steam-inlet ports, a receiver provided with inlet and discharge passages, a segmental plunger working in the receiver and arms connected at one end to a fulcrum-shaft and at the other to the 105 plunger to guide the same, substantially as described.

In testimony whereof I affix my signature in presence of two witnesses.

BROR MAX SCHAUMAN.
